UNITED STATES PATENT OFFICE

SYLVESTER S. JONES, OF CLEVELAND, OHIO

MANICURING DEVICE

Application filed October 27, 1928. Serial No. 315,528.

This invention relates to manicure devices and has for its object the provision of simple compact and easily manipulated mechanism whereby the usual manicure tools can be operated by power, thereby expediting and facilitating the manicurist's labors and saving bodily fatigue. Such power driven devices as have heretofore been known have ordinarily employed peculiar and unconvincing forms of tools which are not readily acceptable either to operators or to their patrons. My improved manicure device employs tools which can be operated interchangeably either by the machine or by hand. In the drawings accompanying and forming a part of this application I have illustrated different views of a single illustrative machine embodying my improvements. Fig. 1 is an elevation of the complete machine equipped with a file; Fig. 2 is a longitudinal sectional view of the machine shown in Fig. 1; Figs. 3 and 4 are sectional views corresponding to the lines 3-3 and 4-4 respectively of Fig. 2; Figs. 5 and 6 are views of the same machine showing different operating parts attached thereto; and Fig. 7 is a sectional view corresponding to the line 7-7 of Fig. 5.

In its preferred form my improved device comprises a hollow handle 1 preferably made in two halves split end to end and held together by suitable screws 2-2, one end of the handle being enlarged and chambered as at 3 for the reception of a bevel gear 4 suitably journaled on the transverse stud 5; and another part of the handle being narrowed as at 6 and provided with a rectangular metal lining 7 in which is slidably mounted a reciprocating rod member 8. One end of this rod is articulated to a pitman 9 whose opposite end is pivoted to an eccentric pin 10 carried by the gear 4; and the opposite end of said rod is equipped with provisions for the attachment of manicure tools. In the present embodiment, and for the purpose of disclosing my idea, I have shown these provisions as comprising a short hook or extension 12 and a long hook or extension 13 both carried by the end of the rod 8 and adapted to enter the apertures

14-14 at the opposite ends of whatever tool is applied thereto, whether a file 15 as shown in Fig. 1 or one of the adapter handles shown in Figs. 5 and 6. Preferably the shank of the hook 13 is sufficiently springy to hold the tools without the need for any mechanical fastenings such as screws or buttons; but it will be understood that I do not limit myself to this construction. 55

Carried by the end of the handle opposite the reciprocating rod is a sleeve member 16 in which is journaled the shank 17 of a rotating element provided at one end with a beveled driving pinion 18 which meshes with the gear 4, and at the other end receives the flexible shaft 19 whereby power is communicated thereto from any kind of motor or other prime mover (not shown). In order to operate a buffer, an adapter handle is employed. In the form here shown this adapter comprises a narrow elongated strip portion 21 having apertures 14 at opposite ends for engagement with the two hooks, and having at an intermediate portion a bracket 22 formed with a socket 23 adapted to receive slidably 65 the back of a buffer 25. 70

In Fig. 6 I have shown another kind of adapter here employed for the attachment of an emery board. In this form I have shown a narrow elongated wood or metal strip 30 likewise having apertures 14 at its ends for the reception of the hooks 12 and 13, and formed at one side with a longitudinally bowed notch 31 terminating in an under-cut shoulder 32 at each end. The emery board 33 is provided at its back with a bracket 34 to which is attached a narrow strip 35 of flexible metal such as spring steel, the length of the strip 35 being such that when braced against the shoulders 32 it is 80 bent longitudinally in accordance with the curvature of the slot 31. The brackets 22 and 34 are made of sufficient length to cause the body of the buffer, emery, and so forth to clear the handle as the device is reciprocated. The body of the file 15, and of the strips 21 and 30 is sufficiently narrow to pass into the sleeve 7 as the tool is operated. 85

It will be understood that many changes in detail can be made without departing 100

from my inventive idea and I do not limit myself except as specifically recited in my several claims which I desire may be construed each independently of limitations contained in other claims.

5 Having thus described my invention what I claim is:

- 10 1. A manicure device comprising a housing, a lining in one end of said housing, a crank element in the other end of said housing, a reciprocable member slidably mounted in said lining, operative connections between said reciprocable member and crank element, a flexible shaft operatively connected to said crank element, and means for securing a manicure tool to the opposite end of said reciprocable member so that a part of said tool passes into said housing at each reciproca-
- 15 2. An adapter element for power driven manicure tools comprising a narrow elongated strip, means for connecting said strip in line with a reciprocating member, a bracket projecting laterally from said strip, and a reciprocable manicure tool carried by said bracket at one side of said strip and parallel thereto.
- 20 3. An adapter element for power driven manicure tools comprising a narrow elongated strip, means for connecting said strip in line with a reciprocating member, a bracket projecting laterally from said strip, said bracket being formed with a socket spaced from said strip, and a manicure tool detachably mounted in said socket.
- 25 35

In testimony whereof I hereunto affix my signature.

SYLVESTER S. JONES.
